(57) **CLAIM**

The ornamental design for a cladding joiner strip, as shown and described.

DESCRIPTION

FIG. 1 is an upper right perspective view of a cladding joiner strip embodying my new design;

FIG. 2 is a right side view of the cladding joiner strip of FIG. 1, the left side being a mirror image thereof;

FIG. 3 is a front view of the cladding joiner strip of FIG. 1;

FIG. 4 is a rear view of the cladding joiner strip of FIG. 1;

FIG. 5 is a top view of the cladding joiner strip of FIG. 1; and,

FIG. 6 is a bottom view of the cladding joiner strip of FIG. 1.

The drawings contain a symbolic break indicated in dot-dash broken lines. The portion between the break lines forms no part of the claimed design. The dash-dash broken lines illustrate portions of the cladding joiner strip that form no part of the claimed design.
